FIRE SHUTTER

Filed Jan. 16, 1930

UNITED STATES PATENT OFFICE

HERMAN GEORGE YOUNG, OF OSWEGO, ILLINOIS

FIRE SHUTTER

Application filed January 16, 1930. Serial No. 421,270.

The object of this invention is to provide easily operated and efficient means whereby a door or window opening may be closed in the event of a fire so that the flames will be confined and may be easily extinguished. The invention is illustrated in the accompanying drawing and will be hereinafter fully set forth.

In the drawing:

10 Figure 1 is an elevation of a fire shutter embodying my invention, the closed position of the shutter being shown by full lines and a partly opened position being indicated by dotted lines,

15 Fig. 2 is a transverse vertical section on the line 2—2 of Fig. 1, and

Fig. 3 is a horizontal detail section on the line 3—3 of Fig. 1.

In carrying out the invention, a frame is 20 erected upon the window or door sill 1 and said frame consists of parallel vertical bars or standards 2 which are arranged in pairs at the opposite sides of the door or window opening, as will be understood, the pairs of 25 standards being connected at their upper ends by cross bars 3 and 4 disposed, respectively, on the inner and the outer sides of the standards whereby to evenly distribute the strain. To the inner side of one of the 30 standards, I secure a plurality of blocks 5 which extend from top to bottom thereof in regularly spaced relation and increase in thickness from top to bottom, as shown in Fig. 2. Pivotaly supported upon the stand-

35 ard by a rivet or bolt 6 passing through the respectively adjacent block are leaves 7 which are adapted to extend across the door or window opening and are so disposed that the lower edge of each leaf will overlap the upper edge of the subjacent leaf. This overlapping arrangement effectually closes all gaps which would otherwise form between adjacent leaves but it causes the leaves to gradually and successively shift in location 40

45 form one standard toward the other standard, as shown in Fig. 2, and for this reason the several fulcrum blocks 5 are successively increased in thickness from the top portion to the bottom block. At the pivoted end 50 of each leaf, there is secured thereto at the

upper outer corner a lever 8 and to the outer ends of all the levers is pivoted a link or operating bar 9, the ends of the upper levers being pivoted at one side of the link while the ends of the lower levers are pivoted at 55 the opposite side of the link so as to compensate for the shifting of the leaves from one standard toward the other standard. The upper end 10 of the link or operating bar 9 has an opening therethrough to facilitate the attachment of a fusible retainer whereby the leaves may be normally held in open position but will automatically close when the retainer is melted.

It will be readily understood that normally the shutter is open, the link or operating bar 9 being swung downwardly and being disposed close to the frame while the leaves will be in an upright position and substantially housed between the standards constituting the 70 frame and if desired a weight may be hung upon the operating bar so that the leaves will be firmly held in the open position. Should a fire occur so that the closing of the shutter would become necessary, the operating bar 9 is pushed upwardly and the impulse thereby transmitted to the several levers 8 will swing the leaves 7 about their respective pivots and bring them at once into the closed overlapping position shown in Figs. 1 and 2 75 of the drawing. All the parts of the structure will, of course, be made of metal of sufficient weight to resist comparatively high temperatures and the leaves will be so balanced that they will swing easily into the closed position when the use of the shutter becomes necessary.

The shutter may, of course, be used in connection with any opening but is designed primarily for use at the openings between projection rooms and auditoriums of motion picture theaters.

Having thus described the invention, I claim:

A fire shutter comprising a pair of standards, a plurality of fulcrum blocks secured on the inner side of one of the standards and successively increasing in thickness from the uppermost block to the lowermost block, 100

leaves pivoted upon said blocks whereby they may extend from the standards to close a window or door opening, levers secured to the leaves at the pivoted ends thereof, and an operating bar pivoted to the free ends of all the levers.

In testimony whereof I affix my signature.

HERMAN GEORGE YOUNG. [L. S.]
